UNITED STATES PATENT OFFICE.

NOAH HARRIS, OF INDIANAPOLIS, INDIANA.

HEEL-SUPPORT.

1,325,845.

Specification of Letters Patent. Patented Dec. 23, 1919.

Application filed May 20, 1916. Serial No. 98,897.

To all whom it may concern:

Be it known that I, NOAH HARRIS, a citizen of the United States, residing at Indianapolis, in the county of Marion and State of Indiana, have invented new and useful Improvements in Heel-Supports, of which the following is a specification.

My present invention pertains to metal heel supports.

10 Experience has demonstrated that the high heel shoes of women, particularly such high heels as describe a concave curve at the breast, frequently break down at the point where the forward part of the heel merges 15 into the sole. This is due in large measure to the fact that heels of the type defined are frequently made of wood.

The object of my invention is to provide a metal heel support, curvilinear in configuration, and constructed and arranged to bridge the broken shank of the shoe, due to the breaking down mentioned, to force the heel back to its initial and normal position and to hold the heel strongly in said position, with the edges of the shank at the break in opposed relation, with the result that the period of usefulness of the shoe is materially prolonged.

To the attainment of the foregoing, my 30 invention consists in the peculiar and advantageous metallic heel support hereinafter described and definitely claimed.

In the accompanying drawings which are hereby made a part hereof:

35 Figure 1 is an inverted plan of a shoe equipped with my novel support.

Fig. 2 is a side elevation of the same.

Fig. 3 is a plan showing the support in the flat state it assumes after undergoing the 40 first process of manufacture prior to its being curved to a greater or less extent to conform to the shape of the heel breast and the arrangement of the heel breast relative to the instep portion of the shoe sole.

45 Similar numerals of reference designate corresponding parts in all of the views of the drawings.

The shoe illustrated is provided with the conventional heel curved at its breast as indicated by 1, and the shoe is shown as broken at the point 2 where the breast of the heel merges into the sole 3.

50 In the absence of my novel metallic support, the fracture 2 would permit the heel to sag forwardly and bring about the destruction of the finished shape of the shoe as well

as materially shorten the wearing capacity thereof.

My novel support 4 is made of sheet-metal and is initially produced in a flat state as 60 shown in Fig. 3, after which it is reduced to concavo-convex form. The heel supports are preferably produced in two forms, one form being curved to a greater extent than the other so that all curved heels may be 65 nicely fitted. The support is curved in the direction of its length, as indicated by 5, is gradually increased in width from its rear end 6 to a point in transverse alinement with the fracture 2, at which point the support 70 is provided with lateral projections 7, and is tapered or reduced in width from the projections 7 to a point adjacent to its forward end. It will also be noticed that in front of the projections 7, the support is 75 flat as indicated by 8; and I would further have it understood that when the sole is slightly curved transversely at the point of the fracture 2, the projections 7 will be correspondingly curved to the same extent. 80

It will be manifest that by reason of the support having the lateral projections 7, the support does not materially increase the weight of or detract from the resiliency of the shoe, and yet is enabled to reinforce the 85 broken portion of the shank throughout the width thereof.

As clearly appears in Fig. 3 the support is provided with apertures at the time of manufacture, and as illustrated in Figs. 1 and 2, 90 the support is fastened to the heel and sole by nails or other fastening devices 9, driven through said apertures.

With the support applied as stated it serves to bridge the break in the shank of 95 the shoe and its lateral projections 7 operate to reinforce and brace the shank portions at opposite sides of the break. The support also serves to force and hold the heel in its initial position so that because of the support the shoe is materially stronger than it was prior to the break. It will also be appreciated in this connection that notwithstanding the strengthening capacity of the support, the same does not appreciably increase the weight of the shoe nor does it detract from the finished appearance of the shoe. It will furthermore be noted that the support embodies but a small portion of metal which contributes to its cheapness, 100 and that being located entirely above the tread portion of the shoe, it does not inter-

fer in any measure with the walking of the wearer.

Having described my invention, what I claim and desire to secure by Letters-Patent, is:

As a new article of manufacture, the herein described metallic support for use on a shoe having a heel the breast of which describes a concave curve and the instep 10 portion of the sole which is transversely broken where it merges into said breast; the said support being in one piece, and comprising a rear portion curved to fit closely the curve of the breast, and a forward ap-

proximately straight portion shaped to fit 15 the sole in both of which are apertures located adjacent to their edges, and also comprising transversely aligned intermediate lateral projections shaped to rest snugly over and against the breast and the instep portion of the sole.

In testimony whereof I have hereunto set my hand in presence of two subscribing witnesses.

NOAH HARRIS.
